His Attorney.

UNITED STATES PATENT OFFICE

2,667,570

MOUNTING BRACKET FOR TUBULAR LAMPS

Harold H. Goldthorpe, Cleveland, Ohio, assignor
to General Electric Company, a corporation of
New York

Application May 5, 1951, Serial No. 224,755

1 Claim. (Cl. 240—51.11)

1
The present invention relates to lighting equipment generally and particularly to such equipment useful for indirect illumination.

An effective lighting scheme for attractively illuminating the rooms of dwellings comprises mounting tubular fluorescent discharge lamps horizontally along the top of the windows and mounting in front of said lamps an opaque baffle in the form of a decorative valance to shield the lamps from view. Difficulty has been encountered in mounting suitable lighting equipment on the window frame because it is necessary to support the lamp ballast, the sockets for the lamps and the valance all in proper relationships.

An object of the present invention is to provide lighting equipment in the form of a fixture readily mounted as a unit on a side wall, such as a window frame, or the like, and adapted to support a lamp shielding member, such as a valance for concealing the lamps and the equipment. Another object of the invention is to provide brackets mountable on a standard wiring channel or raceway and provided with lamp sockets for supporting a tubular lamp between said brackets and having means at the ends thereof for the attachment of a valance. Still further objects and advantages attaching to the invention will be apparent from the accompanying drawing and the following detailed description thereof.

In the accompanying drawing an embodiment of the invention is shown in which, Fig. 1 is a plan view of lighting equipment embodying the invention mounted on a supporting side wall, such as a window frame, and support a horizontally extending valance concealing the lamps mounted in the equipment; Fig. 2 is a perspective view of the end portions of the equipment shown in Fig. 1 with one of the end brackets removed from the raceway to show the attachment means for the brackets; Fig. 3 is a similar view of the component parts of a bracket separated to show the internal structure thereof.

Referring to the drawing the lighting equipment comprises a wiring channel or raceway in the form of an elongated rectangular housing 1 provided with a cover 2 slidable longitudinally in the grooves 3 and 4 along the sides 5 and 6, respectively, of the open front of the housing 1. The cover 2 is thus readily removable for wiring purposes and is firmly held in position on the housing 1 by the grooves 3 and 4.

The housing 1 may be attached to the support 7 (Fig. 1), such as a window frame, in any conventional manner, such as by providing the rear wall 8 thereof with openings (not shown) to ac-

commodate screws for holding the housing 1 on the support wall 7.

End brackets 9 and intermediate brackets 10, of minimum thickness to minimize the space between lamps 11, are mounted and spaced apart on the housing 1 so as to accommodate therebetween tubular fluorescent discharge lamps 11 (Fig. 1) of the same or different standard sizes to suit a particular location. For example, the center lamp 11 may be a 20 watt fluorescent lamp, 24 inches in length and the end lamps 11 may be 15 watt lamps, 18 inches in length. Obviously, the intermediate brackets 10 may be omitted and a single lamp, such as a 30 or a 40 watt lamp, 36 or 48 inches in length, respectively, may be mounted between end brackets 9.

The brackets 9 and 10 are identical in structure and each has outwardly turned end flanges 12 and 13 (Figs. 2 and 3) which are slightly wider than the body of the bracket so that the sides thereof engage the grooves 3 and 4 in the housing 1 to hold the bracket on the housing during assembly. The brackets 9 and 10 are firmly clamped to the housing 1, after the electrical connections have been made between the lamp ballast (not shown) in the housing and the sockets on the brackets, by the threaded bolts 14 passing through openings in the flanges 12 and 13 into engagement with threaded holes in the strips 15. The ends of strips 15 extend underneath the grooved sides 5 and 6 so that the brackets 9 and 10 are firmly clamped on the housing 1.

For safety purposes, the wiring in the housing 1 is completely enclosed by closing the end portions thereof by the short cover portions 16 engaging grooves 3 and 4 and the end pieces 17 holding the said cover portions 16 in place. The end pieces 17 are attached to the housing by the side tongues 18 which fit into the space behind the grooved portions 3 and 4 of sides 5 and 6, and the bottom flange 19 extending into the housing and engaging the bottom wall 8 thereof. The flange 19 and the wall 8 are provided with openings 20 and 21, respectively, to receive the holding pin 22.

The end brackets 9 are each provided with a single lamp socket 23 of a commercial type bolted thereto and the intermediate brackets 10 have a pair of said sockets 23 similarly mounted thereon. The lamp sockets 23 each has a slot 23' therein and are mounted on the brackets 9 and 10 with the said slot 23' opening toward the side of the brackets for receiving the two contact pins on the ends of the lamps 11. The lamps

11 thus can be mounted and dismounted from the side of the unit.

One of the end brackets 9 and each of the intermediate brackets 10 is provided also with a conventional holder 24 (Fig. 3) for a commercial starter switch 25 (Fig. 1). The holder 24 is bolted to the bracket and is disposed within the hollow interior thereof with its current lead wires, together with those of the socket 23, extending from the interior of the bracket into the housing 1. The bracket is provided with an opening 26 opposite the holder 24 for mounting the starter switch 25 one of which is required for each lamp 11.

Both the end brackets 9 and the intermediate brackets 10 are made up of two sheet metal parts 27 and 28 held together by bolts 29 (Fig. 3). Each of said parts 27 and 28 is a duplicate of the other and these parts 27 and 28 are reversed in assembly to make up the bracket. Each part 27 and 28 is made from a strip the end portions of which are bent at right angles to its body portion and one side of which is cut and folded to constitute a side 30 and one-half 31 of the top of the hollow portion of the bracket.

The parts 27 and 28 have knockout portions 32, as shown in part 27 at the left of Fig. 2, which may be removed to provide an opening (Fig. 3) in back of each of the sockets 23 and another opening 26 opposite the starter switch holder 24 where one is mounted in the bracket. The knockout portions 32 may remain in place where these openings are not needed, as in back of holder 24, or when one socket or the holder 24 is omitted, as on the end brackets 9.

The lead wires attached to the socket 23 mounted on the said parts 27 or 28 extend through the opening in the part on which the socket is mounted (Fig. 3) and the starter switch 25 extends through the opening 26 into engagement with holder 24. Bolt holes 32' are provided in diametrically opposed positions and offset from the knockout portions 32 to receive the fastening bolts of the sockets 23 and the holder 24.

The bent end portions 33 and 34 of the parts 27 and 28, respectively, of the brackets 9 and

10 are each provided with openings 35 and 36 so that a lamp shielding member in the form of a valance 37 may be firmly attached thereto by screws 38 as shown in Fig. 1. Obviously, the valance 37 may be translucent and may be attached by other means, such as a pin and socket, to the outer ends of brackets 9 and 10.

From the above it is apparent that the unit is readily mounted on the wall of a room, and particularly on the portion of a window frame above the window, that the valance 37 is readily mounted on the unit, and that the valance, the lamp, and the supporting and auxiliary equipment of the unit are disposed in proper relationship for concealing the lamp and its equipment from view and for ready replacement of the lamp in the unit.

What I claim as new and desire to secure by Letters Patent of the United States is:

A bracket for supporting an elongated tubular lamp and a lamp shielding member on a wiring channel, said bracket comprising two sheet metal strip-like members having their respective end portions extending at right angles to the center portion and in the same direction, the center portion of each strip having a longitudinal edge thereof folded in the opposite direction from said end portions and shaped to engage the center portion of the other of said strips to space said strips, means to fasten said strips together to form a hollow bracket having flanges extending in opposite directions at each end thereof for attachment to the wiring channel and to the lamp shielding member, and a lamp socket mounted on said bracket between its ends to support the lamp between said shielding member and said wiring channel.

HAROLD H. GOLDSMITH.
